UNITED STATES PATENT OFFICE

FLOYD G. WITHROW, OF GRAND RAPIDS, MICHIGAN

BRAKE-ROD SILENCER

Application filed October 21, 1929. Serial No. 401,338.

This invention relates to a brake rod silencer. The brake rods which lead to the brakes of automobiles are of considerable length and in the driving of the car are subject to vibration by reason of road shocks. In order to hold and guide the rods the same passes through a guide member at a point between the ends of the rod and vibration of the rod against the sides of the slot in the guide member many times produces rattles and other undesirable noises which is the primary object and purpose of the present invention to eliminate. An understanding of the construction which has been produced for the attainment of the object stated may be had from the following descriptions, taken in connection with the accompanying drawing, in which,

Fig. 1 is a fragmentary side elevation of a chassis side frame member and the brake rod adjacent the same, the silencer construction of my invention being applied thereto and to the brake rod guide interposed between the chassis frame member and the brake rod.

Fig. 2 is an elevation partly in section of the construction shown in Fig. 1 and,

Fig. 3 is a perspective view of the silencer made in accordance with my invention.

Like reference characters refer to like parts in the different figures of the drawing.

The brake rod 1 is located substantially horizontal a short distance below the adjacent chassis side frame member C and is guided through a slot 2 in the lower end portion of a guide member 3 connected to an outwardly extending leg 4 of a bracket attached to the chassis frame member by means of a bolt 5 which passes through the upper end of the guide member 3 and said leg 4. The slot 2 is elongated vertically and a vibration of the brake rod produces undesirable noises by reason of its contact with the sides of the slot, and the noises and rattling are increased with the age of the automobile and the attendant wear of the brake rod and the sides of the slot 2, as is evident.

The silencer which I have produced to eliminate noises and rattles caused by vibration of the brake rod is made from a single length of spring wire which is bent at its

middle portion to provide a downwardly extending loop 6 the sides of which are continued in reverse loops 7 from which two sides 8 extend downwardly and diverge as shown. The sides 8 are formed at their lower ends and continued as spring coils 9 and from the coils two sections 10 of the wire extend downwardly and inwardly toward each other and cross each other at a point directly below the loop 6. The sections 10 at their ends are turned upwardly and outwardly at right angles making the parts 11 which terminate in return U-bends or hooks 12.

In applying this silencer to the brake rod, its guide and chassis frame member, the upper central loop 6 is inserted upwardly between the guide member 3 and the chassis frame member so as to bear against the lower edge of arm 4. One of the sections 10 is located at one side or back of the brake rod 1 and the other at the other side or in front thereof with a coil 9 at each side of the lower end portion of the guide member 3. The sections 10 are then sprung upwardly so as to hook the hooks 12 over the brake rod 1 one at each side of and a short distance from the guide member 3 for the brake rod.

In thus applying the silencer the coils 9 are tensioned considerably and the sides 8 and sections 10 sprung out of shape so that the effect is to force the brake rod in a downward direction snugly against the lower end of the slot 2 in the guide member 3. This insures against vibration of the rod and striking against the sides of the slot which causes rattling noises.

The construction described is simple to manufacture and easily made and very quickly applied without the use of tools or employment of skilled labor. Noises coming from vibration of the brake rods and striking of the same against the sides of the slot in the guide member are completely eliminated irrespective of the extent of wear which may have occurred on both the brake rod and the sides of the slot. The invention is defined in the appended claims and is to be considered comprehensive of all forms of structure coming within their scope.

I claim:

1. A device of the class described formed from a single length of spring wire, bent at its middle portion to provide a downwardly extending loop open at its upper side and thence continued to form reversed loops at each side of the first loop, said reversed loops being continued to provide downwardly and outwardly extending sides, spring coils formed at the lower ends of said sides and straight sections extending from said coils downwardly and inwardly toward and across each other, each of said sections at its free end being bent at right angles for a short distance and then bent back upon itself to form a U-shaped hook.
2. A construction of the class described formed from a single length of spring wire material and bent at its middle portion to provide two downwardly extending sides spaced apart from each other and integrally connected at their upper ends, spring coils at the lower ends of said sides formed as continuations thereof, wire sections extending from the coils downwardly and inwardly toward and across each other, each of said sections at its free end being bent at right angles for a short distance and then bent back upon itself to form an open hook.
3. In combination, a motor vehicle chassis side frame member, a bracket secured to and extending outwardly therefrom, a guide member pivotally mounted at its upper end on and depending from said bracket and having a vertical slot in its lower portion, a horizontal rod passing through said slot, and spring means located between said bracket and rod and bearing at its upper end against said bracket and having detachable connection with said rod at two points, one at each side of the guide member, said spring means being sprung out of normal form when connected to said rod thereby subjecting the rod to downward pressure.
4. In combination with a motor vehicle chassis side frame member, a guide member pivotally connected at its upper end to and depending from said frame member, said guide member having a vertical guide slot at its lower portion, a rod passing through said slot, and a spring device formed from spring wire material bent to have an upper end portion to engage against the support for said guide member and having downwardly extending sides with spring coils intermediate the ends thereof, and hook means at the free ends of said sides to engage over said rod and exert a downward pressure thereon, said sides of said spring device being sprung out of normal shape when engaged with said rod.

In testimony whereof I affix my signature.

FLOYD G. WITHROW.
